UNITED STATES PATENT OFFICE.

EMERY H. FAHRNEY, OF CHICAGO, ILLINOIS.

SNOWPLOW.

Application filed April 29, 1928. Serial No. 105,350.

This invention relates in general to snow plows for removing snow from streets, roads, or highways, the apparatus embodying an impeller or rotor for receiving and delivering the snow from the machine, and a scoop like device for gathering and directing the snow to the impeller.

In machines of this character it has been found that the snow will pack within the scoop and will pile up at times to such an extent that it will fall out of the front of the scoop in advance of the machine, with the result that the operation of the machine will be impaired.

It is one of the objects of the present invention to provide improved means in connection with the scoop for assisting in conveying the snow to the impeller, and for breaking up and disintegrating the snow as it is delivered to the impeller or rotor.

A further object is to provide improved means for use in connection with the scoop for breaking up the snow which has accumulated and become packed within the scoop, and for feeding and transferring the snow from the top of the pack or pile to the rotor or impeller to be delivered thereby from the machine.

To the attainment of these ends and the accomplishment of other new and useful objects as will appear, the invention consists in the features of novelty in substantially the construction, combination, and arrangement of the several parts, hereinafter more fully described and claimed and shown in the accompanying drawings illustrating this invention; and in which,

Figure 1 is a longitudinal sectional view taken on line 1—1 Figure 2 of an apparatus of this character constructed in accordance with the principles of this invention.

Figure 2 is a top plan view of Figure 1 with parts broken away.

Figure 3 is a side elevation taken on line 3—3 Figure 2.

Figure 4 is a side elevation taken on line 4—4 Figure 2.

Referring more particularly to the drawings, the numeral 10 designates generally a supporting structure preferably mounted upon wheels 11 and at the rear of the supporting structure is arranged a casing 12 having an inlet 13 and delivery outlet 14. This casing is pivotally mounted in any suitable manner upon the structure 10 and is shaped to contain a rotor 15 of any suitable

construction. The rotor is operated from a power shaft 16 through the medium of intermeshing gears 17, 18, 19 the gears being so arranged with respect to each other that the casing 12 may be swung about its pivot without interfering with the operation of the rotor.

Associated with the casing 12 is a scoop like device 20 having its forward end open and arranged to direct the snow into the casing 12 through the opening 13 and to the rotor 12.

Arranged at the bottom of the scoop are a plurality of shafts 21 extending lengthwise thereof, and these shafts are preferably provided with blades 22 for propelling the snow, and additional blades 23 for breaking up or disintegrating the snow.

Any number of these shafts 21 and blades 23 may be provided. The forward ends of the shafts are preferably mounted in suitable bearings 24 and the rear ends in suitable bearings 25, the latter being preferably located in the rear of the scoop and the shafts pass through suitable openings in a cover portion 26.

The bearings 25 are preferably formed in the wall of a casing 27, and within the casing is arranged a shaft 28 having gears 29 thereon which mesh with the gears 30 on the ends of the shafts 21 for rotating them.

Motion is imparted to the shaft 28 through the medium of a gear 31 connected thereto outside of the casing 27, and this gear meshes with a gear 32 on a shaft 33 mounted in suitable bearings 34. Connected with the shaft 33 is another gear 35 which meshes with a gear 36 on a shaft 37 to which the gear 18 is connected.

Thus it will be seen that when the shaft 37 is rotated through the drive shaft 16, the rotor 15 will be rotated, and motion will be imparted to the shafts 21 for rotating the blades 22 to assist in feeding the snow through the scoop and into the opening 13 to the impeller 15.

Journalized in suitable bearings in the sides of the scoop is a casing 38 within which is a shaft 39 that has bearings in the end of the casing. One end of the shaft 39 projects through the end of the casing 38 and also one of the side walls of the scoop, and has connected therewith a gear 40 which meshes with a gear 41 on a shaft 42.

A gear 43 is also connected with the shaft 42 and meshes with a gear 44 on the shaft

37, so that the motion of the shaft 37 will be transmitted through the gear connection to the shaft 39.

The casing 38 forms a portion of a frame like structure embodying a cross bar or member 45 which is spaced from and connected with the casing by means of spacing bars or rods 46, and shafts 47 are journaled at one end in bearings in the wall of 10 the casing 38, and at their other ends in bearings in the member 45.

Blades 48 are connected with the shafts 47 for assisting in feeding the snow to the impeller.

15 Connected with each of the shafts 47 and within the casing 38 are gears 49, which mesh with the gears 50 on the shaft 39 for imparting rotation to the shaft 47 and the blades 48.

20 The casing 38 is adapted to be rotated in its bearings so as to raise and lower the shaft 47 and the blades 48 connected thereto, to cause them to bodily move in directions toward and away from the bottom of 25 the scoop. These shafts 47 and blades 48 are so arranged that they will operate upon the top of the pile of the accumulated or packed snow within the scoop to assist in feeding it to the rotor.

30 Any suitable means may be provided for moving the casing 38 about its pivot to raise and lower the shafts 47 and blades 48 and to maintain them in their adjusted position.

To that end there may be provided a 35 worm gear 51 which is connected with the casing 38 preferably on the outside of the scoop. Meshing with this worm gear is a worm 52 provided with a handle 53 for rotating it. By rotating the worm 52 a rotary 40 movement will be imparted to the casing 38, so that the shafts 47 with the blades 48 thereon may be moved in directions toward and away from the bottom of the scoop, as indicated in Figure 1, and without interfering 45 with the rotation of the shafts 47.

With this improved construction, it will be manifest that there is provided a scoop like device which may be positioned at any desired angle with respect to the surface of 50 the ground and means are provided within the scoop which will assist in delivering the snow to the impeller.

The blades 22 will operate upon the supply of snow near the bottom of the pile, 55 while the blades 48 will act upon the top of the pile to deliver the material therefrom. This will prevent the snow from packing in the scoop and the efficiency of the machine will be greatly increased, at the same time 60 the blades 48 and shafts 47 will not be in a position that they will interfere with the delivery of the snow to the impeller.

While the preferred form of the invention has been herein shown and described, it is 65 to be understood that various changes may

be made in the details of construction and in the combination and arrangement of the several parts, within the scope of the claims without departing from the spirit of this invention.

What is claimed as new is:—

1. A snow plow embodying a rotor, a scoop like structure for delivering snow to the rotor, means adjacent and fixed with respect to the bottom of the scoop for assisting in carrying the material to the rotor, means within and adjacent the top of the scoop for feeding the material from the top of the supply, and means mounting the last recited means for adjustment towards and 75 in close proximity to and also away from the first said means.

2. A snow plow embodying a rotor, a scoop like structure for delivering snow to the rotor, means adjacent and fixed with respect to the bottom of the scoop for assisting carrying the material to the rotor, means within and adjacent the top of the scoop for feeding the material from the top of the supply, and means mounting the last 80 recited means for adjustment towards and in close proximity to and also away from the first said means, the second recited means embodying a plurality of separate 85 conveyors.

3. A snow plow embodying a rotor, a scoop like structure for delivering snow to the rotor, means adjacent and fixed with respect to the bottom of the scoop for assisting in carrying the material to the rotor, means within and adjacent the top of the scoop for feeding the material from the top of the supply, and means mounting the last 90 recited means for adjustment towards and in close proximity to and also away from the first said means, both the first and second recited means embodying a plurality of conveyors respectively independent of each other.

4. A snow plow embodying a rotor, a scoop like structure for feeding the snow to the rotor, a plurality of conveyors adjacent the bottom of the scoop for feeding the snow to the rotor, a plurality of separate conveyors adjacent the top of the scoop for feeding the snow from the top of the supply to the rotor, means pivotally mounting the last recited conveyors by one end, and means for swinging the last recited conveyors about said end and towards and away from the first said conveyors.

5. A snow plow embodying a rotor, a scoop like structure for feeding the snow to the rotor, a plurality of conveyors adjacent the bottom of the scoop for feeding the snow to the rotor, a plurality of separate conveyors 125 adjacent the top of the scoop for feeding the snow from the top of the supply to the rotor, means pivotally mounting the last recited conveyors by one end, means for swinging the last recited conveyors about said end and 130

towards and away from the first said conveyors, and means common to the rotor and all of the said conveyors for operating them.

6. A snow plow embodying a rotor, a scoop like structure for feeding the snow to the rotor, a plurality of spiral conveyors adjacent the bottom of the scoop for feeding the snow to the rotor, a plurality of separate spiral conveyors adjacent the top of the scoop for feeding the snow from the top of the supply to the rotor, means pivotally mounting the last recited conveyors by one end, means for swinging the last recited conveyors about said end and towards and away from the first said conveyors, a power shaft, and gear connections between the said shaft and the rotor and the said conveyors.

7. A snow plow embodying a rotor, a scoop like structure for feeding the snow to the rotor, means adjacent the bottom of the scoop for assisting in feeding the snow to the rotor, a plurality of conveyer blades pivotally mounted by one end and operable to feed the top portion of the supply of material to the rotor, and means for swinging the said conveyer blades about their pivots in directions towards and away from the first recited means.

8. A snow plow embodying a rotor, a scoop like structure for feeding the snow to the rotor, means adjacent the bottom of the scoop for assisting in feeding the snow to the rotor, a plurality of conveyer blades pivotally mounted by one end and operable to feed the top portion of the supply of material to the rotor, means for swinging the said conveyer blades about their pivots in directions towards and away from the first recited means, and means common to the said rotor, the first recited means and the said conveyer blades for actuating them.

9. A snow plow embodying a rotor, a scoop like structure for delivering snow to the rotor, conveying means within and adjacent the bottom of the scoop for assisting in feeding the material to the rotor, a frame like structure within the scoop and mounted by one end for pivotal movement in directions towards and away from the bottom of the scoop, conveying means mounted in said

frame, means for actuating the last recited conveying means, and means for swinging the said frame about its pivot at will.

10. A snow plow embodying a rotor, a scoop like structure for delivering snow to the rotor, conveying means within and adjacent the bottom of the scoop for assisting in feeding the material to the rotor, a frame like structure within the scoop and mounted by one end for pivotal movement in directions towards and away from the bottom of the scoop, conveying means mounted in said frame, means for actuating the last recited conveying means, means for swinging the said frame about its pivot at will, a power shaft, and a gear connection between the said power shaft and the second recited conveying means.

11. A snow plow embodying a rotor, a scoop like structure for delivering snow to the rotor, a conveyer shaft within and extending lengthwise of the scoop, conveyer blades on the shaft, means embodying a housing extending in a direction transverse to the scoop for pivotally mounting said shaft by one end, actuating means for the said shaft and embodying gear mechanism within said housing, and means for swinging the shaft about its pivot, the said conveyer blades operating to feed the top of the supply of material to the rotor.

12. A snow plow embodying a rotor, a scoop like structure for delivering snow to the rotor, a conveyer shaft within and extending lengthwise of the scoop, conveyer blades on the shaft, means embodying a housing extending in a direction transverse to the scoop for pivotally mounting said shaft by one end, actuating means for the said shaft and embodying gear mechanism within said housing, and means exterior of the scoop and embodying worm gearing for swinging the said shaft about its pivot and for maintaining the same in its adjusted position.

In testimony whereof, I have signed my name to this specification this 23rd day of April, 1926.

EMERY H. FAHRNEY.
